UNITED STATES PATENT OFFICE.

ARTHUR W. HAHN, OF NEW YORK, N. Y.

BRUSH.

SPECIFICATION forming part of Letters Patent No. 519,948, dated May 15, 1894.

Application filed May 27, 1893. Serial No. 475,759. (Model.)

To all whom it may concern:

Be it known that I, ARTHUR W. HAHN, of New York city, in the county and State of New York, have invented a new and Improved 5 Brush for Nursing-Bottles, of which the following is a full, clear, and exact description.

My invention relates to an improvement in brushes, especially brushes adapted for use in cleaning nursing bottles, or like vessels or 10 receptacles; and the object of the invention is to provide a brush in which the bristle or cleaning section thereof will be removably connected with the back section, thereby admitting of a brush section being removed from 15 the back when unfit for use and another brush section substituted.

A further object of the invention is to so construct the brush section that any one capable of using the brush may apply a brush section to a back section.

Another feature of the invention consists in not attaching the bristles directly to the back section, but in bunching and securing bristles in brush form independent of the 25 back, and in so attaching the brush section to the back section that a cleaning surface will be obtained practically on three sides of the back and at one end thereof.

The invention consists in the novel construction and arrangement of the several parts, as 30 will be hereinafter fully set forth, and pointed out in the claim.

Reference is to be had to the accompanying drawings, forming a part of this specification, 35 in which similar figures and letters of reference indicate corresponding parts in all the views.

Figure 1 is a side elevation of the brush, illustrating its application to a bottle. Fig. 2 40 is a partial side elevation and partial sectional view of the back section, and a longitudinal section through the brush section, illustrating the manner in which it is applied to a back section. Fig. 3 is a plan view of a 45 slightly modified brush; and Fig. 4 is a partial plan view of the back with the brush section detached.

The back section A of the brush is provided 50 usually at one end with a crank arm 10, which crank arm serves as a handle; and the handle member of the crank arm may be given any shape that fancy may dictate or conven-

ience may demand. The back, from the crank arm to a point near its center, is preferably made substantially straight, as illustrated at 55 11 in the drawings; and where the straight portion of the back ends the said back is curved or depressed in a downward direction, and is then straight throughout the rest of its length. Ordinarily the depressed portion of the back is flattened, as at this point the bristle or cleaning section B of the brush is to be attached; but the other portions of the back may be made, and preferably are made circular in cross section, and usually the entire back is made from a single piece of wire rod.

The brush or bristle section B of the brush may be made of any desired length, and the bristles or any substitute therefor that may 70 be employed, are secured in any suitable or approved manner to a core 12, preferably of a flexible character. In fact, the core is ordinarily made of twisted wire of suitable size, and the bristles or other substitute that may 75 be employed, are held in engagement with the core, the attachment being so effected that the bristles radiate from the core in direction of all sides, or practically so. The flattened or outer depressed portion of the back is ordinarily provided near its inner end with an aperture 13, and at its outer extremity the said depressed portion of the back is provided with a recess 14 and an aperture 15 adjacent to the recess, as shown in Fig. 4. 85

The cleaning or bristle section of the brush is attached to the back in the following manner: One end of the wire core 12 of the cleaning or bristle section is passed down through the aperture 15, and then the said section is 90 carried around the end of the back section, the wire or core entering the recess 14 thereof, and thence along the under surface of the said back section to the aperture 13, when the other end of the core 12 is passed up 95 through said aperture and bent down upon the back section as shown most clearly in Fig. 2. When the core is carried up over the end of the brush, the bristles are carried up with it, so that the outer end of the back is concealed or covered by bristles; and it will be readily observed that practically the cleaning or bristle section is attached to the back section at two points only, and that while it 100

will remain firmly in place it may be expeditiously and conveniently removed from the back when worn or unfit for use, and another bristle section may be substituted for it by 5 any one having the power to bend the core.

In Fig. 3 I have shown a slight modification in which one end of the core is tied around the back instead of being passed through the aperture in the back. I further desire it to 10 be understood that although the shape of back illustrated in the drawings is preferred, it may have other cross sectional shape, or it may be made straight if in practice it is found desirable; but by depressing the brush end of 15 the back, and forming a crank arm at the handle end, the brush may be turned in a bottle or decanter, for example, as shown in Fig. 1, in such manner that the bristle or cleaning section will engage with the entire interior 20 surface of the bottle when the handle section is revolved, and the bristles at the end of the back will thoroughly clean the bottom of the bottle.

Such a brush is exceedingly simple, it is durable and it is economic in its construction, 25 and it is especially adapted for cleaning a nursing bottle, as all the crevices may be reached with it, and none of the inner surface will escape from the action of the brush.

Having thus described my invention, I 30 claim as new and desire to secure by Letters Patent—

A brush comprising a back section having a recess in one end, and an aperture adjacent to said recess, and a brush section provided 35 with a wire core having projecting ends said brush section having one end of its core secured in the aperture of the back section with the core resting in the recess of said back section, and the other end of its core secured 40 to the back section, substantially as herein shown and described.

ARTHUR W. HAHN.
